UNITED STATES PATENT OFFICE.

CHARLES H. BEERS, OF ASBURY PARK, NEW JERSEY.

NON-REFILLABLE BOTTLE.

1,097,745.

Specification of Letters Patent. Patented May 26, 1914.

Application filed July 14, 1913. Serial No. 778,818.

To all whom it may concern:

Be it known that I, CHARLES H. BEERS, a citizen of the United States, and residing at Asbury Park, in the county of Monmouth and State of New Jersey, have invented 5 certain new and useful Improvements in Non-Refillable Bottles, of which the following is a specification, such as will enable those skilled in the art to which it appertains to make and use the same.

This invention relates to bottles, jugs, jars and similar vessels, and the object thereof is to provide a vessel of this class which having been once filled and emptied of its contents 15 cannot be refilled or reused.

The invention is fully disclosed in the following specification of which the accompanying drawing forms a part, in which the separate parts of my invention are designated by suitable reference characters in 20 each of the views, and in which:—

Figure 1 is a central vertical section of a top portion of a bottle provided with my improvement; Fig. 2 a similar view but 25 showing parts in a different position, and; Fig. 3 a cross section on the line 3—3 of Fig. 1.

In the practice of my invention, as shown 30 in the drawing, I provide a bottle *a* having a neck *b* which is of the usual form except that, in the construction shown, the bottom portion *b*² of said neck is slightly enlarged and provided on its inner side with vertical grooves *b*³, and at the bottom of the enlargement *b*² is an inwardly directed annular ledge or shoulder *c* forming an annular valve seat and a central port or passage *c*², and at 35 the top thereof is an annular ledge or shoulder *c*³. That part of the neck between the annular ledge or shoulder *c*, and the annular ledge or shoulder *c*³ forms a valve chamber 40 or space in which is placed, as hereinafter described, a valve or valve device, but the construction of the bottom part of the neck *b* is immaterial, except that the grooves *b*³ are preferably formed therein for the purpose herein described, and the diameter of the top portion of the neck must be such as to permit of the passage, downwardly there- 45 through, of the valve or valve device, as herein described.

Placed on the annular valve seat is a gasket *d* of cork or other suitable material, and placed on the gasket *d* is a vertically mov- 50 able cylindrical valve device *e* having a projecting annular bottom rim or flange *e*² and

a similar top rim or flange *e*³, and said valve device is free to move vertically in the space in the walls of which the grooves *b*³ are formed, and wound on the body portion of said valve device is a fine spring *f* which normally bears on the bottom flange or rim *e*² and normally holds said valve device seated on the gasket *d*, and the top portion of the spring *f* is provided with a laterally directed member *f*² adapted to bear on the bottom of the ledge or shoulder *c*³, and in the form of construction shown, the laterally directed part or member *f*² of the spring *f* is provided with an upwardly directed finger *f*³ for this purpose. I also place in the neck *b* a guard *g* intended to prevent interference with the operation of the valve device *e* as hereinafter described, and said guard, in the form of construction shown, consists 60 of a transverse concavo-convex diaphragm or partition *g*² the rim of which is provided with a depending skirt *g*³ in which is formed an annular groove in which is placed a spring ring *g*⁴, and the inner walls of the neck of the bottle are provided just above the space in which the valve device *e* is movable with an annular groove *b*⁴ to receive 65 said spring ring. The part *g*² of the guard is provided with radial slits *g*⁵ forming 70 corresponding sectoral parts *g*⁶, and one wall of each of the slits *g*⁵, or one edge of each of the sectoral parts is depressed, as shown at *g*⁷, and this construction, while permitting the contents of the bottle to flow out, as 75 hereinafter described, and also prohibit the insertion of wire or other instrument in the effort to interfere with the operation of the valve device and the guard will, as will be seen, also aid in preventing the removal of 80 the valve or valve device from the neck of 85 the bottle.

In the use of my improved bottle or other vessel of this class, the vessel is first filled with the desired contents after which the valve device *e* is inserted into and passed downwardly through the neck until it rests in the position shown in Fig. 1, in which position it is held by gravity, and also by the spring *f*. The guard *g* is then inserted 90 into the neck, and said neck may be closed by the usual cork or stopper.

When it is desired to empty the bottle, or discharge a portion of its contents, the cork or stopper is removed and the bottle 100 is inverted or tilted in the usual manner, and the valve device *e* will drop forward

or into the position shown in Fig. 2, when the contents of the bottle will flow out through the neck, and this operation may be continued or repeated until the bottle 5 or vessel is emptied of its contents.

When the bottle is held in an upright position, the port or passage c^2 is closed by the valve device e , and no liquids can be poured into the bottle and the bottle 10 cannot be refilled.

The spring f is preferably just strong enough to hold the valve device e seated when the bottle is inverted, and no liquids can be forced into the bottle when held in 15 such position. The valve device e , however, may be made to serve as a float, in which case, said valve device will rise and close the port or passage c^2 , if an attempt be made to fill the bottle by forcing liquids 20 thereinto, while said bottle is held in an inverted position, but I prefer to make the spring f sufficiently strong to hold the valve device e seated when the empty bottle is inverted, as in this case, any appreciable 25 amount of liquid in the bottle would open the valve device when the bottle is inverted or tilted and permit said liquids to flow out as will be readily understood.

It will be understood that my invention 30 is not limited to the particular form of the guard g herein shown and described, and any preferred device of this class may be employed.

Having fully described my invention what 35 I claim as new and desire to secure by Letters Patent is:—

1. A bottle or similar vessel provided with a neck in the bottom of which is an

annular valve seat, said neck being also provided above said valve seat with vertical 40 grooves in the inner walls thereof, and a cylindrical valve device placed in the bottom portion of the neck and adapted to rest on said valve seat, said valve device being freely movable in that portion of the 45 neck in which said grooves are formed, and the body portion of said valve device being less in size than the end portions thereof, and a spring wound on the body portion 50 of said valve device and having a projecting member operating in connection with a part of the neck of the bottle to hold the valve device seated, said neck of the bottle being also provided with a guard which is secured therein above the valve device. 55

2. A bottle or similar vessel provided with a neck in the bottom of which is an annular valve seat, said neck being also provided above said valve seat with an annular shoulder forming in connection with said 60 valve seat a valve chamber, a cylindrical valve device placed in said valve chamber and adapted to rest on said valve seat, and freely movable in said chamber, a spring 65 connected with said valve and one end of which bears on said shoulder, and passage ways between the valve and the walls of the valve chamber.

In testimony that I claim the foregoing as my invention I have signed my name in 70 presence of the subscribing witnesses this 8th day of July, 1913.

CHARLES H. BEERS.
